(57) **CLAIM**

The ornamental design for the spray head for a container, as shown and described.

DESCRIPTION

FIG. 1 is a front elevation view of a spray head for a container showing the invented design.

FIG. 2 is a left side elevation view thereof.

FIG. 3 is a right side elevation view thereof.

FIG. 4 is a top plan view thereof.

FIG. 5 is a bottom plan view thereof.

FIG. 6 is a top, front and left perspective view thereof.

FIG. 7 is a bottom, rear and right perspective view thereof.

FIG. 8 is a cross-sectional view along Line 8-8' of FIG. 4.

FIG. 9 is a front elevation view thereof in a state of spray.

FIG. 10 is a left side elevation view thereof in the state of spray.

FIG. 11 is a right side elevation view thereof in the state of spray.

FIG. 12 is a top plan view thereof in the state of spray.

FIG. 13 is a bottom plan view thereof in the state of spray.

FIG. 14 is a top, front and left perspective view thereof in the state of spray; and,

FIG. 15 is a cross-sectional view along Line 15-15' of FIG. 12.
